UNITED STATES PATENT OFFICE

CHRISTIAN N. BROTHERSON, OF KETCHIKAN, TERRITORY OF ALASKA

PISTOL

Application filed February 4, 1928, Serial No. 251,833. Renewed May 12, 1931.

The present invention relates to a pistol, and aims to provide a novel and improved device of this character which will provide for automatic operation as well as manual 5 operation between the explosion of cartridges therein, thus providing an automatic and bolt locking pistol.

Another object of the invention is to provide a pistol of this general character having 10 a rigid frame with the front and rear sights in fixed position, and for permitting the holding of the pistol with both hands without danger of injury thereto, this being accomplished by having the sliding breech 15 block arranged interiorly of the frame.

A further object of the invention is the provision of ample safety devices for preventing accidental discharge of the pistol, said safety devices consisting of a lock for 20 the sear when the grip is released, a manually operated lock for the sear, and a trigger safety for preventing operation of the hammer when the magazine is removed.

A still further object of the invention is 25 to provide a slidable firing pin on a sliding breech, said firing pin being moved by engagement with an abutment upon rear movement of the breech, so that said firing pin besides firing cartridges acts in conjunction 30 with an extractor on the breech for ejecting shells from the pistol.

As another object of the invention, I provide a pistol consisting of three main units, namely: barrel and slide casing, sliding 35 breech, and handle section, which are held in operative assembled position by a main assembly bolt passed through said slide casing and handle section; thus the pistol may be easily and conveniently taken apart for 40 cleaning, etc., upon removal of the assembly bolt.

It is also an object of the invention to provide a pistol of the above indicated character, which is substantial in construction and 45 which will be thoroughly efficient and practical in use.

With the foregoing and other objects in view, which will be apparent as the description proceeds, the invention resides in the construction and arrangement of parts, as

hereinafter described and claimed, it being understood that changes can be made within the scope of what is claimed, without departing from the spirit of the invention.

The invention is illustrated in the accompanying drawings, wherein:

Figure 1 is an elevation of one side of my improved pistol,

Figure 2 is an elevation of the other side thereof,

Figure 3 is a vertical longitudinal section through the pistol, showing the end of the barrel broken away, the mechanism being illustrated in the position ready for firing,

Figure 4 is a similar view showing certain parts in elevation and the mechanism with the breech in its rear position after firing,

Figure 5 is a longitudinal horizontal section taken on line 5—5 of Figure 3,

Figure 6 is a vertical section taken on line 6—6 of Figure 5 and being a view somewhat similar to Figures 3 and 4, showing the device in a position when the hammer engages the firing pin prior to rearward movement of the breech block,

Figure 7 is a rear elevation of the pistol,

Figure 8 is a vertical cross section taken on line 8—8 of Figure 6,

Figure 9 is a fragmentary section taken on line 9—9 of Figure 3,

Figure 10 is a perspective view of the breech removed from the pistol,

Figure 11 is a fragmentary vertical section taken on line 11—11 of Figure 8,

Figure 12 is a fragmentary horizontal cross section taken on line 12—12 of Figure 3,

Figure 13 is a fragmentary section taken on line 13—13 of Figure 6, and

Figure 14 is a longitudinal horizontal section taken on line 14—14 of Figure 3.

The pistol constructed in accordance with my invention consists of three main units, the barrel and hollow casing section A, the slidably mounted breech B, and the handle section C containing the magazine D. The barrel and casing section A are attached to the handle section C while the sliding breech is mounted within the casing A and upon the upper surface of the handle section C.

The casing 15 of the section A is rigidly carried by the rear end of the barrel 16 which terminates within the casing 15. The casing 15 has a top wall 17 and side walls 18 and 19, said side walls extending forwardly a short distance past the rear end of the barrel 16 and being closed at their forward ends by wall 20. Adjacent the rear end of the top wall 17 of the casing 15 is mounted a rear sight 21, while on the forward end of the barrel 16 is mounted a front sight 22, whereby said front and rear sights are carried by rigidly attached members, so that they remain in a fixed position and do not change with relation to each other during operation of the gun.

In the opposite side walls 18 and 19 of the casing 15 directly opposite each other is a pair of grooves 23 into which engage longitudinal ribs 24 carried by the handle section for forming a connecting means for attaching the section A to the section C. The handle section C has a forward extension 25 between the side walls 18 and 19 of the casing 15 at the forward ends thereof and adjacent their bottom edges so that said forward extension forms the lower wall of a chamber 26. The forward end of this extension is notched, as at 27, to correspond with the end portion 20 of the casing 15 for interlocking engagement. In order that the barrel and casing section A will be held against sliding movement with relation to the handle section C, an assembly bolt 28 extends through the opposite side walls 18 and 19 of the casing adjacent their rear ends and through the rear portion of the handle section C. Thus it can be seen that the barrel and casing section A is held against movement away from the section C by the grooves and ribs 23 and 24 respectively and the interlocking connection 27, and that said connected barrel and casing section are held against sliding movement with relation to the handle section C by the assembly bolt 28.

Slidable between the side walls 18 and 19 of the casing 15 is a breech 29, consisting of a breech block 30 having extending rearwardly therefrom a pair of spaced bars 31 and 32 which are connected together at their rear ends by a block 33, while extending forwardly of the breechblock 30 is another pair of spaced bars 34 and 35 which have their forward ends connected together by means of a block 36. The bars 34 and 35 are arranged on a plane below the block 30 and slide within the compartment 26 formed by the forward ends of the side walls 18 and 19 of the casing 15 and the forwardly extending portion 25 of the handle section 16. Extending upwardly from the rear portion of said forward extension between the bars 34 and 35 is a lug 37 which is engaged by the head 38 of a guide pin 39 extending forwardly through an opening 40 in the block

36 and has a coiled retracting spring 41, which engages against the block 36 and against the head 38 of the guide pin. The purpose of the retracting spring is to yieldably hold the breechblock forwardly in engagement with the rear end of the barrel 16. 70

When in firing position, the breechblock 30 is at the rear end of the barrel 16 in alignment with the bore 41' so as to hold a cartridge during the firing thereof. Slidable in the breechblock 30 is a firing pin 42 adapted to strike the rim of the cartridge in the barrel 16 upon forward movement of said pin, said pin working in a bore 43, enlarged as at 45, to receive a coil spring 46 80 encircling the firing pin. One end of the coil spring 45 engages the forward end of the bore 45 and the other end engages an enlarged end 47 on said firing pin so as to yieldably hold it in rearward position. The enlarged portion 47 of the firing pin is notched, as at 48, into which extends a key pin 49 for preventing the firing pin from being entirely forced from the bore within which it slides, it being understood that the notch 48 is of sufficient length to permit required movement of the firing pin.

As the rear end of the casing 15 is open, it can be seen that when a cartridge is fired the explosion thereof will force the slideable breech backward against tension of the retractor spring 41, and that after the force of the explosion is relieved said spring will return the breech to its forward position into engagement with the rear end of the barrel. 95 As it is necessary to remove the shell of the cartridge from the bore 41' of the barrel, an extractor 50 is carried by the breechblock 30 on the forward end of which is a hook portion 51 engaging the rim of the shell in order to cause said shell to be moved rearwardly with the breech. The extractor 50 is located in a recess 52 in the side of the breechblock and is pivoted therein by means of a vertical pin 53 extending through said extractor and into the breechblock, said pin being intermediate the ends of the extractor, the latter being engaged at the end thereof opposite to the hook portion 51 by a small coil spring 54 within a recess 55 in the breechblock. It can be seen that the coil spring urges the hook shaped portion 51 of the extractor in a position so as to engage the rim of the shell, said hook shaped portion having a beveled face 56 on the forward end thereof to permit it to move forwardly of the rim when the breech is moved in a forward direction. On the side wall 19 of the casing 15 at its rear end is an abutment lug 57 against which the firing pin engages when the breech is moved rearwardly so as to force the firing pin forwardly in the breechblock and cause the shell to be swung to a cocked position due to the fact that the hook portion 51 of the extractor is still in engagement 110 115 120 125 130 135

therewith. Upon further forward movement of the firing pin in the breechblock, the spent shell will be thrown through an opening 58 in the side wall 18 of the casing 15. At the forward end of the breechblock 30 is a pair of projecting pins 57 for the purpose of preventing side movement of a cartridge during the period the hook shaped end 51 of the extractor is engaged over the rim of the cartridge, said forwardly projecting pins engaging the opposite edge of the rim of the cartridge from that engaged by the extractor and at points above and below the firing pin 42.

15 In order that provision may be made for having the pistol hand operated I provide a locking bolt 59 for preventing the breech from being forced rearwardly by the explosion of a cartridge, said bolt having the opposite ends 61 and 62 reduced and journaled in the breechblock 30 and upstanding portion 63 of the block 33 with a lug 64 at one side so that upon turning movement of the bolt said lug will be moved to a position in engagement with the abutment 57 on the side wall 19 of the casing; thus the lug 64 will prevent the breech from sliding rearwardly on the explosion of a cartridge. Upon the rear end of the reduced portion 62 of the locking bolt is secured a turn button 65 for manipulating the locking bolt so that the pistol may be used automatically or hand operated. One side of the turn button 65 is arcuate, as at 66, and provided with a pair 35 of shoulders 67 and 68 adapted to be yieldably engaged by a small leaf spring 69 carried by an extension 70 on the rear portion of the block 33. The shoulders 67 and 68 are located on the turn button so as to hold the locking bolt in either of its positions, namely out of engagement therewith or in engagement with the abutment 57. In order that the turn button may be easily turned, a finger 71 projects therefrom to be engaged by a 40 hand of the operator.

The handle section C consists mainly of a casing 72 having opposite side plates 73 and 74 connected together at their forward edges by a wall 75, and in rear of this wall in spaced 45 parallel relation thereto is a partition wall 76. Said forward wall 75, partition wall 76 and side plates 73 and 74 form the magazine compartment into which the magazine D is slid from the lower end of the handle section 50 or stock C. The upper ends of the front wall 75 and partition wall 76 terminate below the upper end of the handle section C and the upper end of the magazine is supported by means of a pair of spaced blocks 78 and 79, arranged between the side plates 73 and 74, the block 78 heretofore referred to by the numeral 37, being forwardly of the upper end of the magazine, while the block 79 is rearwardly thereof.

55 The magazine D consists of a casing hav-

ing side walls 80, front wall 81, rear wall 82, and a base 83, the latter extending partially into the casing and has a pin 84 passed therethrough and through the opposite side walls 80, so that said base is firmly connected to the casing. At the forward end of the base is a forwardly extending lug 85 to be engaged by a finger of the operator in order to remove the magazine from the handle section or stock C. In the upper portions of the side walls 80 of the magazine D are longitudinal slots 86, 87, and 88, so as to form spring fingers 89, 90, and 91 for engaging the uppermost cartridges contained in the magazine so as to yieldably hold said cartridge until released. By referring to Figures 4, 6, and 8, it can be seen that the upper ends of the fingers engage a cartridge, and in Figure 8 the fingers 91 are slightly curved inwardly so as to prevent a cartridge from moving beyond the ends thereof, said curved portions being designated by the numeral 92. Within the magazine D is a slideable cartridge push block 93, which has its lower portion reduced in thickness, as at 94, and about which is arranged the upper end of a coil spring 95, while the lower end of the coil spring 95 engages the base 83. Thus it can be seen that the push block 93 will be urged upwardly so as to move the cartridges to the upper end of the magazine.

10 By referring to Figures 3, 6, and 8, it can be seen that when the breech 30 is in its forward position against the rear end of the barrel 16 the upper end of the magazine is positioned directly thereunder. On the lower rear end of the breech 30 is a depending lug 96, which has a vertical shoulder 97 and a rearwardly inclined face 98, the purpose of which will be set forth as the description proceeds, while at the forward lower portion of the block 30 is arranged a forwardly extending lug 99, which has its lower surface gradually rounded, as at 100. The forward portion of the lug 99 is adapted to engage the rear end of the uppermost cartridge 101 in the magazine 77 as soon as the breech starts to move forwardly, thus forcing this cartridge forwardly until the rear end thereof has passed from under the curved portions 92 of the upper ends of the fingers 91 and the forward end of the cartridge has started to enter the bore 41' of the barrel 16. At such time, the spring 95 in the magazine will force the cartridge upwardly above the fingers 91 and the forward end 102 of the breechblock will force the cartridge into the bore of the barrel. A small leaf spring 103 is carried by the upper wall 17 of the casing 15 so as to prevent the forward end of a cartridge being forced past the bore 41', thus aiding in aligning the cartridge with the bore prior to its entrance therein. The upper end of the block 78 is forked, as at 104, while a notch is provided

in the rear end of the barrel 16 at the lower portion of the bore which also provides guides for directing the forward end of the cartridge in the bore. The notch 105 receives the forwardly extending lug 99 when the breech 30 is in its forward position. It can be seen that when a cartridge is forced into the barrel the hook 51 of the extractor 50 will be forced outwardly so as to permit the same to engage over the rim of the cartridge. In order that the hook shaped portion 51 of the extractor 50 will not engage the end of the barrel 16 a notch 106 is provided in the end of the barrel for receiving the hook 51 upon forward movement of the breech.

Extending through the handle section or stock C and journaled in the side plates 73 and 74 thereof is a pin 107 which pivotally supports a hammer 108, said hammer having on its free end an enlarged head 109. The pin 107 is located so that when the hammer 108 is swung on its pivot in a forward direction the head 109 thereof will engage the enlarged end 47 of the firing pin so as to discharge a cartridge. By providing the inclined surface 98 on the lug 96 of the breech, the hammer 108 will be moved backwardly upon rearward movement of the breech for recocking the hammer. Below the pivot pin 107 is another pivot pin 110, the opposite ends of which are received in the side plates 73 and 74 of the handle section or stock C, upon which is pivotally mounted a sear 111, the pin extending through the sear intermediate its ends. The upper end of the sear engages a shoulder 112 on the hammer adjacent the pivot thereof for holding the hammer in cocked position. In order that the sear will be yieldably held in a position to engage the shoulder 112 when the hammer is moved backwardly a leaf spring 113 is provided, one end of which is attached to the block 79, while the other end engages the sear. To one side of the pivot of the hammer 108 is a small extension 113' which is forked and in which is a pivot pin 114 supporting a T-shaped stirrup 115 providing a crossbar 116 at the free end thereof engaged by the upper forked end 117 of a spring member 118. The spring member 118 is substantially U-shaped to provide a pair of leg portions 119 and 120, the leg portion 119 having the forked end 117 thereon and being of greater length than the leg portion 120, while the leg portion 120 engages a small lug 121 at the upper end of the partition wall 76 and the side thereof engages the rear side of said partition 76, as clearly shown in Figure 3 of the drawings. The bight portion 122 of the U-shaped spring member 118 is curved slightly to one side and

engages into a small recess 123 in the lower end of a movable grip member 124. The general tendency of the legs 119 and 120 is to move away from each other. As the leg 120 is held against movement, the leg 119 ⁷⁰ will form a means for throwing the head 109 of the hammer 108 forwardly as soon as the sear 111 is moved from engagement with the notch 112 on the hammer. The lower end of the U-shaped spring member 118 forms ⁷⁵ another function which will be set forth as the description proceeds.

At the inner sides of the side plates 73 and 74 of the handle section or stock C are recesses 125, which receive side bars 126 of a sear trip 127 (Fig. 4), said bars extending beyond opposite sides of the magazine 77. The opposite ends of the bars 126 are connected at their forward and rear ends by cross-pieces 128 and 129, respectively. The forward cross-piece 128 has a forwardly extending lug 130 which is received in a small notch 131 in the rear side of a trigger 132, said notch being arranged adjacent the lower free end of the trigger. The upper end of the trigger is pivotally supported by means of a pivot pin 133 which extends through the trigger and into the opposite side plates 73 and 74 of the handle section or stock. In order that the trigger trip 127 will remain in operative relation with the trigger, a leaf spring 134 is carried by the forward end of the sear trip 127 and has its upper end bearing against the front wall 81 of the magazine. Thus it can be seen that the general tendency of the sear trip is to remain in its forward position, which will return the trigger to its initial or forward position. The rear connecting portion 129 of the bars 126 of the sear trip is provided with a shoulder 135 which engages the lower depending end of the sear so as to swing the same on its pivot and thus cause the upper end of said sear to be disengaged from the notch 112 of the hammer 108 against tension of the sear spring 113. It can be seen that the leaf spring 134 also holds the rear end of the sear trip upwardly and in engagement with the lower end of the sear. When the magazine 77 is removed from the handle section or stock the free end of the spring 134 not having an element to engage will permit the rear end of the sear trip to drop, thus providing a safety so as to prevent discharge of a cartridge remaining in the barrel after the magazine has been removed.

The forward bar 35 of the sliding breech is provided with a cam surface 136 which engages a cam surface 137 on the upper end of a finger 138 carried by one of the side bars 126 of the sear trip. The recess 125 in the side plate 74 extends upwardly so as to receive the finger 138 and is of sufficient size to permit movement of said finger therein. By providing such cam surfaces are such that ¹³⁰

when the sliding breech moves rearwardly they will engage, thus forcing the sear trip 127 downwardly so that the rear end having the shoulder 135 thereon will be disengaged 5 from the sear to prevent the disengagement of the sear from the notch 112 in the hammer 108 until the sliding breech has moved to its forward position. This mechanism provides another safety device which will prevent the 10 discharging of a cartridge before the breech-block is in a position to properly support the cartridge. By referring to Figure 4 it can be seen how the sear trip is held in such position, the finger 138 being illustrated in 15 dotted lines.

The rear wall of the handle section or stock C is formed by the movable member 124, which is pivotally mounted at its lower end, as at 139, the pivot pin extending through 20 said movable member 124 and through the opposite side plates 73 and 74 of the handle section. At the point of the movable member 124, the same is enlarged which permits the forming of the recess 123 which the bight 25 portion 122 of the U-shaped spring 118 engages, said enlarged portion also forming an abutment for one end of a coil spring 140 which is positioned in a recess 141 arranged in the lower end of the partition 76. The opposite end of the coil spring 140 engages an 30 inwardly projecting lug 142 carried by a magazine latch 143 that extends slightly under the base 83 of the magazine and may be moved from beneath the same by sliding the magazine latch against tension of the coil 35 spring 140. The recess 141 is enlarged at its inner portion and the lug 142 is of a similar shape so as to prevent the disconnection of the magazine latch from the handle section or stock C. When the magazine latch and coil 40 spring 140 therefor are installed they are placed in the recess 141 prior to the releasing of the pivot pin 139 for the movable member 124 through the side plates 73 and 74 of the handle section or stock C. It can be seen that 45 the coil spring 140 will normally hold the magazine latch in a position to prevent removal of the magazine from the handle section or stock C and that the U-shaped spring 50 118 engages the movable member 124 above the pivot thereof so as to hold the movable member 124 outward with the upper end in engagement with the lower end of a rear spacing block 144, the same being the block 55 through which the assembly bolt 28 extends.

The recesses 125 in the opposite side plates 73 and 74 of the handle section or stock C extend upwardly at the point where the upper end of the movable member 124 is arranged 60 so that said upper end may slide within said recess. The upper portion of the movable member 124 is of a channel shaped construction presenting a back portion 145 having forwardly extending side 65 portions 146 which are received in the recesses

125. One of the side portions 146 is provided with a notch extending therein from its forward upward edge, said notch being designated by the numeral 147. Extending into the notch 147 is the free end 149 of a pivoted sear locking member 148 pivoted upon the bolt 107 which pivotally mounts the hammer 108 and carries at the side thereof a right angularly extending lug 150 which is adapted to be moved downwardly when the sear locking member 148 is swung on its pivot so as to cause said lug to move in front of the upper end of the sear 111 to prevent disengagement of the upper end of the sear from the notch 112 in the hammer 108. From this 70 structure it can be seen that when the pistol is held in the hand of the operator it will be necessary to force the movable member 124 forwardly when the trigger is pulled rearwardly. Upon forward movement of the pivoted movable member 124, the free end 149 of the sear locking member is moved in a downward direction so as to cause the right angularly extending lug 150 to be moved upwardly and out of the path of movement of the 80 sear 111 which will permit said sear to release the hammer. When pressure is relieved on the movable member 124, the U-shaped spring 118 will return the same to its initial position and the notch 147 in said 85 movable member will cause the free end or finger 149 to be moved upwardly and the right angularly extending lug 150 to be moved in the path of movement of the sear so as to hold said sear against movement out of engagement with the notch 112 of the hammer 108. 90

In order that the sear 111 may be manually locked against disengagement from the notch 112 in the hammer 108, there is a small arm 151 provided with a right angle extension 152, the arm being integral with the pivot pin 107 arranged upon the opposite sides of the hammer 108, as clearly shown in Figure 13 of the drawings. The pivot pin 107 may be turned within the side plates 73 and 74 of the handle section or stock C by means of a lever 153 at one end thereof, and when it is desired to manually lock the sear from engagement with the notch 112 in the hammer said lever is moved downwardly so that the right angularly extending portion 152 of the arm 151 is in the path of movement of the sear to prevent disengagement of the sear from the notch 112, thus providing another safety device for my improved pistol. 105

In operation, to remove the magazine D from the handle section or stock C the magazine latch is slid rearwardly until the forward end by forcing thereof disengages the magazine and the finger engaging lug 85 115 downwardly the magazine will slide from the handle section or stock C. The magazine is filled with cartridges by sliding them inwardly, rim first, under the curved portions 92 of the fingers 91, which will force the push 120 125 130

block 93 downwardly against tension of the coil spring 95. The magazine is then replaced in the handle section or stock C and the magazine latch permitted to return so as to engage the lower portion of the base 83 of the magazine. If the pistol is to be used as an automatic the turn button 65 is arranged so that the lug 64 on the locking bolt 59 extends downwardly and out of engagement with the abutment shoulder 57. By then engaging the turn button and pulling the sliding breech backwardly against tension of the retractor spring 41, the hammer 108 will be moved rearwardly to a cocked position with the sear 111 in engagement with the notch 112 in the hammer, said sear serving the purpose of holding the hammer in cocked position. The turn button is then released so as to permit the breech to return to its forward position. As soon as the breech starts to return, the forwardly extending lug 91 thereon will engage the uppermost cartridge in the magazine and slide the same forwardly. The cartridge is guided into the bore 41' of the barrel 16 by the inclined face on the block 78 and the fingers 89 and 90 of the magazine. The cartridge is moved forwardly until the rim thereof prevents forward movement thereof, at which time the hooked end 51 of the extractor 50 will be forced outwardly and permitted to engage over the rim of the cartridge. The spring 103 together with the forwardly extending pins 57' and the hooked end 51 of the extractor will aid in properly supporting the cartridge during the forcing thereof into the bore of the barrel.

The manual sear lock is then raised by moving the finger engaging member 153 on the handle section or stock in an upward direction, which will cause the angularly extending portion 52' to move above the upper end of the sear. The pistol is then ready for firing, and as soon as the handle section or stock is gripped and pressure applied on the trigger and the movable rear wall 124 of the stock, the cartridge in the bore of the barrel will be fired. It is to be noted that it is necessary for the movable portion 124 of the handle section or stock to be moved forwardly before the trigger will release the sear from the shoulder 112 on the hammer, as the angularly extending portion 151 on the member 148 is arranged in advance of the upper end of the sear and will prevent movement thereof. The right angularly extending portion 150 is raised upwardly by swinging the member 148 on the pivot pin 107, such movement being had due to the connection of the finger 149 of the member 148 with the movable member 124 of the handle section or stock. The pull on the trigger will move the sear trip rearwardly, and as the same engages the lower end of the sear, the same is swung on its pivot against tension of the sear spring 113. As soon as the upper end of the sear disengages the shoulder 112 of the hammer 108, said hammer will be forced forwardly by the U-shaped spring 118. The head 109 of the hammer will strike the enlarged rear end of the firing pin 42 and force the same forwardly against tension of the coil spring 46 and cause the forward end of the firing pin to suddenly engage the rear of the shell of the cartridge adjacent the rim thereof. As soon as the cartridge is fired, the explosion thereof will cause the breech to be moved rearwardly. As the hook shaped portion 51 of the extractor 50 has engaged over the rim of the shell, the shell will be drawn from the rear end of the barrel and moved with the breech. Prior to the extreme rear movement of the breech, the rear end of the firing pin will engage the abutment shoulder 57 which will cause said firing pin to be moved to still further forward position. As the shell is not rigidly supported at such time, the firing pin will cause the same to be swung due to the engagement of the hook shaped member 51 with the rim thereof until said hook shaped member has released the shell and it is thrown outwardly through the opening 58 in the side wall 18 of the casing 15. Also, the rearward movement of the breech will cause the hammer to be returned to its initial position, due to the fact that the inclined surface 98 engages the head of the hammer and forces the hammer rearwardly as shown in Figure 4 of the drawings. At such time, the upper end of the sear will engage the shoulder 112 of the hammer and thus hold the hammer in such position when the breech returns to its forward position. Upon the returning of the breech, another cartridge is engaged by the forwardly extending lug 99 and forced into the rear end of the bore of the barrel. Figure 3 shows the position of the various elements when the pistol is about to be fired. Figure 4 shows the various parts in position when the breech is at its rear end of movement. Figure 6 shows the various parts at the time of firing of a cartridge, the latter illustrating the hammer 108 in engagement with the firing pin, with the trigger 132 and movable member 124 in depressed position.

When it is necessary to recock the pistol and remove the shell by hand, the turn button 65 is turned so that the lug 64 engages the abutment shoulder 57, which will prevent rearward movement of the breech upon the firing of a cartridge. After a cartridge has been fired, it is necessary to turn the turn button 65 so that the lug 64 disengages the abutment shoulder 57 and then pull the breech rearwardly against tension of the retractor spring 41. The removal of the shell from the bore of the barrel and the placing of a new cartridge in the bore is the same as when the pistol is operated automatically,

the only difference being that it is necessary to manually pull the breech rearwardly.

It is to be noted that the opposite side bars 34 and 35 at the forward end of the breech 5 are arranged on opposite sides of the lug 78 and that the bar 35 extends rearwardly a greater distance than the bar 34 and is provided with a cam surface 136 which engages the cam surface 137 of the upstanding finger 138 carried by the sear trip 127, such elements being clearly illustrated in Figure 11 of the drawings, which will cause the rear end of the sear trip to be moved downwardly and held in such downward position until the 10 breech has returned to its forward position, thus preventing the releasing of the hammer to fire another cartridge prior to the proper returning of the breech block 30 to a position in engagement with the rear of the barrel 16. 15

As previously stated, when the magazine is removed from the handle section or stock C, the rear end of the sear trip is permitted to drop, due to the fact that the magazine has been moved to a position so that there is 20 nothing to engage the spring 134 in order to hold the rear end of the trip in proper position. This prevents the firing of a cartridge remaining in the bore of the barrel during the period the magazine is removed 25 from the pistol.

Having thus described my invention, what I claim as new is:

1. A pistol comprising a casing including a barrel and a handle section, a sliding breech arranged in said casing, a block on said breech adapted to engage the rear end of said barrel when the breech is in its forward position, said breech being adapted to be moved rearwardly by the explosion of a cartridge 35 in the barrel, spring means for returning said breech to its forward position, a firing pin carried by said breech block, a pivoted hammer having a shoulder thereon, a spring urged sear adapted to engage the 40 shoulder on said hammer to hold the same in cocked position, spring means for forcing said hammer forwardly upon release thereof by said sear, a sear trip adapted to engage said sear in order to move the same out of engagement with the shoulder of said hammer upon movement thereof, a trigger arranged for moving said sear trip, a magazine for feeding cartridges to the barrel of the pistol upon movement of said sliding breech, a leaf spring carried by said sear trip and in engagement with the magazine for holding the sear trip in position in engagement with the sear, and an extension on said sear trip and adapted to be engaged by said sliding breech when the same is in its rearward position so as to force said sear trip against tension of said leaf spring out of engagement with said sear. 55

2. A pistol comprising a casing including a barrel and a handle section, a sliding breech

arranged in said casing, a block on said breech adapted to engage the rear end of said barrel when said breech is in its forward position, said breech being adapted to be moved rearwardly by the explosion of a cartridge 78 in the barrel, spring means for returning said breech to its forward position, means for firing a cartridge in the barrel, a locking bolt carried by said sliding breech, an abutment shoulder arranged on said casing, a lug on 75 said locking bolt, and means for engaging said locking bolt in order to turn the same into engagement with said abutment shoulder in order to prevent sliding movement of said breech by the explosion of a cartridge 80 in the barrel.

3. A pistol comprising a casing including a barrel and a handle section, a sliding breech arranged in said casing, a block on said breech adapted to engage the rear end of 85 said barrel when said breech is in its forward position, said breech being adapted to be moved rearwardly by the explosion of a cartridge in the barrel, spring means for returning said breech to its forward position, means for firing a cartridge in the barrel, a locking bolt carried by said sliding breech, an abutment shoulder arranged on said casing, a lug on 90 said locking bolt, means for engaging said locking bolt in order to turn 95 the same into engagement with said abutment shoulder in order to prevent sliding movement of said breech by the explosion of a cartridge in the barrel, and means for yieldably holding said lug on said locking 100 bolt in either of its positions.

4. A pistol comprising a casing having a barrel and a handle section attached to said casing with longitudinal ribs at the inner faces of the side walls of said casing, a handle section having side walls provided with longitudinal grooves for slidably receiving said ribs of said casing, a forward extension on said handle section forming a bottom wall of a compartment below the rear portion of 105 said barrel, a sliding breech arranged above the handle section, bars formed integrally with and extending forward from the lower portion of said breech into said compartment, the forward end of said bars being connected by a crosspiece, a coil spring in engagement with the crosspiece and with the handle section at the rear end of the compartment, a block carried by said breech and adapted to engage the rear end of the 110 barrel when the breech is in its forward position, said breech being adapted to be moved rearwardly by the explosion of a cartridge in the barrel against tension of said spring, a firing pin carried by the breech, and a hammer adapted to engage said firing pin. 115 120 125
